(57) **CLAIM**

The ornamental design for a suspension module, as shown and described herein.

DESCRIPTION

FIG. 1 is a full side view of a suspension module showing a right end extended adaptor tube;

FIG. 2 is a full right end view of the suspension module of FIG. 1 showing an inside snap ring;

FIG. 3 is a cross sectional side view taken through line 3-3 of FIG. 2. This view is intended to show the position and depth of the snap ring in the suspension module, and,

FIG. 4 is a full left end view of the suspension module of FIG. 1 showing the distal end of an adaptor tube.
